(57) CLAIM

The ornamental design for a carrying case, as shown and described.

DESCRIPTION

FIG. 1 is a perspective view of a carrying case showing my new design;

FIG. 2 is a front elevation view thereof;

FIG. 3 is a rear elevation view thereof;

FIG. 4 is right side elevation view thereof;

FIG. 5 is a left side elevation view thereof;

FIG. 6 is a top plan view thereof;

FIG. 7 is a bottom plan view thereof; and,

FIG. 8 is a second perspective view of the carrying case showing my new design with additional environment.

The broken lines shown represent environment and form no part of the claimed design.

1 Claim, 6 Drawing Sheets
